US0D1083143S

(12) United States Design Patent (10) Patent No.: US D1,083,143 S
(45) Date of Patent: * Jul. 8, 2025

(54) HUT

(71) Applicants: Maximilian Schade, Graz (AT); Fritz Walter, Graz (AT)

(72) Inventors: Maximilian Schade, Graz (AT); Fritz Walter, Graz (AT)

() Term: 15 Years

(21) Appl. No.: 35/520,332

(22) Filed: Feb. 28, 2024

(80) Hague Agreement Data

Int. Filing Date: Feb. 28, 2024

Int. Reg. No.: DM/235678

Int. Reg. Date: Feb. 28, 2024

Int. Reg. Pub. Date: Mar. 22, 2024

(51) LOC (15) Cl. 25-01

(52) U.S. Cl.

USPC D25/18; D25/20; D25/21; D25/32; D25/33

(58) Field of Classification Search

USPC D21/506, 507, 511; D25/1, 4, 6, 17–18, 52/234

CPC .. E04H 1/005; E04H 1/02; E04H 1/12; E04B 2001/0092

See application file for complete search history.

(57) CLAIM

The ornamental design for a hut as shown and described.

DESCRIPTION

The file of this patent contains at least one drawing/photograph executed in color. Copies of this patent with color drawings/photographs will be provided by the Office upon request and payment of the necessary fee.

1. Hut

1.1 : Front

1.2 : Right

1.3 : Top

1.4 : Back

1.5 : Perspective

1.6 : Perspective

1.7 : Perspective

The interior structures visible through the grayed window panes of the hut form no part of the claimed design.

1 Claim, 7 Drawing Sheets
(7 of 7 Drawing Sheet(s) Filed in Color)
